(57) **CLAIM**

The ornamental design for a display screen or portion thereof with animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view showing a first image in a sequence for a display screen or portion thereof with animated graphical user interface;

FIG. 2 is a second image thereof;

FIG. 3 is a front view showing a first image in a sequence for an alternate embodiment for a display screen or portion thereof with animated graphical user interface; and,

FIG. 4 is a second image thereof.

The broken lines shown in the figures of a display screen are for the purpose of illustrating portions of the article, and form no part of the claimed design.

**1 Claim, 4 Drawing Sheets
(4 of 4 Drawing Sheet(s) Filed in Color)**
